UNITED STATES PATENT OFFICE.

HENRY ROESKE, OF PHILADELPHIA, PENNSYLVANIA, ASSIGNOR TO
EMANUEL PRINTZ, OF PHILADELPHIA, PENNSYLVANIA.

APPARATUS FOR DEGREASING SUBSTANCES.

No. 810,223.

Specification of Letters Patent.

Patented Jan. 16, 1906.

Application filed January 6, 1905. Serial No. 239,722.

To all whom it may concern:

Be it known that I, HENRY ROESKE, a citizen of the United States, residing in the city and county of Philadelphia, State of Pennsylvania, have invented a new and useful Apparatus for Degreasing Substances, of which the following is a specification.

My invention consists in a novel apparatus with which I promote the efficiency of naphtha or other material with like property in the extracting of grease from substances.

Figure 1 represents a vertical sectional view of a degreasing apparatus embodying my invention. Fig. 2 represents a plan view thereof. Fig. 3 represents a plan view of the upper portion of the operating-tank with portions of the device removed. Fig. 4 represents an elevation showing the operating means in detached position. Fig. 5 represents a plan view of the gears employed. Figs. 6 and 7 represent sectional views of a valve employed, showing the same in different position.

Similar numerals of reference indicate corresponding parts in the figures.

Referring to the drawings, 1 designates an open operating-tank which is supported in any convenient manner, in the present instance by the standards 2, said tank having a suitable door 3 in one side thereof for the insertion and removal of the substances to be treated, the upper wall of said tank being provided with an opening 4, across which extends the bar 5, which forms a support for parts of the mechanism, to be hereinafter described.

6 designates a plate situated in the lower portion of the tank, having an opening 7 therethrough, while the lower wall of said tank is provided with the extension 8, which supports the bearing 9, through which passes the shaft 10, the latter having a gear 11 thereon meshing with the gear 12, carried by the shaft 13, which is suitably supported and to which power is supplied in any convenient manner. On the bearing 9 is rigidly secured the beveled gear 14, which is in mesh with the gears 15, suitably supported and carried by the shaft 10, said gears having pins 16 and 17 thereon, with which are connected the rods 18 and 19, the latter extending upwardly through the opening 7 and being connected with pins 20 and 21, carried by the wheels 22, the latter being supported on the shaft 23,

which is mounted in a suitable hanger 24, 55 which is carried by the bar 5 and passes through the opening 25 therein. On said rods are the drums 26, beyond which are the adjustable collars 27, so that the position of the drums 26 can be adjusted on the rods 18 60 and 19.

28 designates rods which are adapted to be inserted in the openings on the drums 26 and serve as a support for the substances to be treated.

29 designates a steam-jacket, which in the present instance is placed beneath the tank, to which steam is supplied through a pipe 30, a suitable vent or escape 31 being provided for the jacket, it being understood that said jacket can be of any size and placed at any suitable point adjacent the tank 1. Steam is conducted to the pipe 30 through the pipe 32, which leads from any suitable source of supply and is provided with a suitable valve 33 75 for controlling the same. Situated between the inlet of the pipe 32 and the outlet of the pipe 30 is a valve 34 in said pipe, said valve being of any desired form and in the present instance consisting of a casing 35, having an opening 36 therein. Within said casing 35 is a valve 37, having ports adapted to register at the proper time with said openings 36 in the casing 35. Connected with said valve 37 is a rod 38, carrying an adjusting-weight 39 85 and connected with an arm 40, carrying a plunger 41, the latter being situated and movable in a casing 42, around which is the jacket 43, forming a chamber therebetween which is in communication with the interior of the 90 tank 1 by means of the pipes 44 and 45. Situated within the casing 42 beneath the plunger is a column of mercury 46, so that said plunger 41 is actuated by expansion and contraction of said mercury 46. Connected with the 95 steam-inlet 32 is a pipe 47, being provided with a suitable valve 48 and having two branches 49 and 50, communicating, respectively, with the periphery of the turbine 51, so that steam is supplied thereto, either at its 100 axis or its periphery, in order to rotate the same in either a right or left direction. Connected with the turbine is a shaft 52, which is mounted in a suitable bearing and is provided with a gear 53, which meshes with the gear 105 54, with which is suitably connected a fan 55, the support for said gear 54 and fan being upon the bar 5, said fan being so situated as

to rotate directly over the opening 4 in the top of the tank.

56 designates a hood which covers the opening 4, and in which hood said fan 55 rotates, the upper portion of said hood being connected by a pipe 57, which communicates with the interior of a heater 58, same consisting of a suitable casing in which are mounted the heating-coils 59, steam for which is supplied through the pipe 60, connected with the steam-inlet 32, and which is provided with a suitable valve 61 for controlling the steam to the coil 59, a suitable outlet for said steam being provided by the pipe 62. From 15 the upper portion of said heater 58 leads a pipe 63, which communicates with the interior of the condenser 64, the latter having a water-jacket 65 therearound and which forms the chamber 66, into which compressed air is adapted to be passed through the pipe 67 for the purpose of promoting the cooling capacity of the water which may be fed into said chamber 66 through the pipe 68, a suitable vent 69 being provided for the said 20 chamber, through which the compressed air may pass out. Through the condenser 64 passes a plurality of tubes 70, open at their ends, so that the vapors from the heater 58 pass around these pipes, and I provide baffle- 25 plates 71 on the interior of the condenser in order to give a greater path of travel for the vapor in the condenser. The left baffle-plate is provided with holes at its lower portion to permit the liquid from the last compartment 30 to reach the outflow 74.

72 designates a vent-pipe which allows the outflow of the liquid from the tank 64 whenever the valves in connection therewith and for the purpose hereinafter described are operated.

The liquid from the tank 64 can be guided into the storage-tank 78 through the pipes 74 and 76, and from the tank 78 it may be carried into the vessel 1 by means of pipe 77, the 45 valve 75 being then closed. If for some reason the communication with the storage-tank 78 should be interrupted, the liquid from the tank 64 may be directly guided into the vessel 1 by opening the valve 75 and closing the valves in the pipes 76 and 77. From 50 the bottom part of the vessel 1 leads a pipe 73 into the tank 64 for the purpose of conducting up the remaining vapor for liquefaction, as will more fully be described herein- 55 after.

The operation is as follows: The substance is placed upon the arms 28 and is submerged by the degreasing material—such as, for instance, naphtha. A sufficient time, according 60 to the nature of the substance, is given the naphtha to soak the substance, after which heat is applied by passing steam into the jacket 29 and placing the weight of the temperature-valve to the proper point. At 65 this same time power is furnished to the tur-

bine 51 in order to rotate the fan 55 in such a direction as to draw off the vapor from the vessel as fast as it is generated and to carry it through the hood 56, pipe 57, heater 58, and pipe 63 into the condenser 64, wherein it 70 becomes liquid. Said liquid is then permitted by the open vent 72 to escape through the pipes 74 and 76 into the storage-tank 78, the valve 75 and the valve in the pipe 77 being closed. When by evaporation the surface 75 line of the naphtha has reached a point below the substance, the mixture of naphtha and grease is carried off through the pipe 79 and the actual degreasing process is over. What now follows is the scouring of the substance 80 in order to remove that portion of the grease or oil which has been extracted from the interior of the substance, but still clings to its outside. Fresh naphtha is then supplied to the tank 1 by opening the valve in the pipe 85 77, and power is applied to the shaft 13 in order to rotate the arms 28, carrying the substance. When this has continued the required time, the naphtha is withdrawn again through the pipe 79, and the remaining vapor is driven up through the pipe 73 into the 90 cooler 64 for liquefaction by reversing the action of the turbine 51 and fan 55. Said vapor could perhaps be drawn off in the manner employed during the actual degreasing 95 process; but as the fresh naphtha supplied for the scouring leaves cooler gases behind which have more the natural tendency to descend than to ascend it is deemed more practical to drive them out through the pipe 73. 100 After all this has been accomplished the substance is withdrawn from the vessel 1 through the door 3. The purpose of carrying the vapor drawn from the vessel during the actual degreasing process on its way to 105 the cooler through a heater is to keep the vapor as a vapor until it reaches the cooler; otherwise and in the event the pipes 63 should necessarily be carried to a distance making up and down bends, &c., a portion of 110 the vapor would liquefy, filling up low points of the conduit, forming traps, and preventing further passage of the vapor. The heater as well as the fan force are therefore essential. The difference of operation with this apparatus in comparison with former is that in 115 the former the vapor of the naphtha remains in the operation-tank, and therefore limits the evaporation, so as to leave the substance submerged until the liquid is drained off. In 120 this draining off the surface line of the liquid falls from the top part of the substance to below, but this is for no other purpose and with no other effect but to drain off, and it is deemed profitable to accomplish this removal as rapidly as possible to gain time. In 125 my operation the vapor is constantly withdrawn by force, thus avoiding pressure and promoting evaporation, the surface line of the liquid lowering constantly and slowly 130

from top to below in order to subject every part of the substance to the higher action of the liquid at its surface line, which is deemed the most efficient point of action.

5 It will be evident that various changes may be made by those skilled in the art which will come within the scope of my invention, and I do not, therefore, desire to be limited in every instance to the exact construction herein shown and described.

Having thus described my invention, what I claim as new, and desire to secure by Letters Patent, is—

15 In a device of the character described, an operating-tank adapted to be filled with degreasing material, supports for the material

to be treated therein, a condenser, conduits leading from the top and bottom of the tank to said condenser, and a propeller above said supports adapted to rotate in two directions, 20 whereby the air or vapor in said tank is removed therefrom by drawing the same through the upper conduit, while the substances are in part submerged by the material that is in the tank and forcing the air or 25 vapor through the lower conduit, after all the material has been withdrawn or changed into vapor.

HENRY ROESKE.
